WARNER T. TABB, OF MAHWAH, NEW JERSEY.

CLAMP.

Application filed November 11, 1925. Serial No. 68,410.

My invention relates particularly to clamps for retaining hair on hair curlers but more generally applies to clamps of the adjustable type adaptable to grip cylindrical bodies and others, of various sizes.

An object of my invention is to provide a clamp adapted to grip bodies of various sizes without previous adjustment of the clamp, and which will automatically adjust 10 itself within limits to the shape and size of the body.

A further object is to provide such a clamp as above which, will in various degrees of extension required, provide a reasonably uniform gripping pressure against said 15 body.

A particular object is to provide such a clamp as above which will be suitable for use with a hair curler, to hold the hair in a 20 wound condition on the spindle on which it is wound.

A more particular object is to provide such a clamp as the above adaptable for use, without previous adjustment, with hair of various lengths and various amounts of hair of 25 a given length; or briefly, with various sized bobbins of hair.

A further object is to provide a clamp 30 which will give a reasonably uniform wrap or degree of inclosure of various sizes bobbins of hair, and which may be adjustable while in place to give a greater or less wrap as desired.

A further object is to provide such a 35 clamp as above, which when used with a hair curler of the class having a heating element internal of a spindle, or other means of heating the hair in position, will provide an insulating means to protect the body of the user from contact with the heated portions of the curler.

A further object is to provide a clamp for 40 such purposes as above which may be simple of construction and easily attachable to, and removable from, the bobbin or other body with which it is used.

The above and other objects of this 50 invention will be made clear by the accompanying drawing which shows certain approved embodiments of the invention, and the following description:

In the drawing:

Figure 1 shows in end view a clamp according to this invention, in gripping position on a body shown in transverse section. 55

Figure 2 is a front elevation of Figure 1 showing a portion of the body in dotted lines.

Figure 3 is a plan view of the same clamp and body seen from above Figure 2. 60

Figure 4 shows in end view the same clamp as above gripping a body of larger size, shown also in section.

Figure 5 shows the same clamp in its free position unattached to any body. 65

Figure 6 is a sectional view of a resilient member of the above clamp, in its free condition. The section is taken on a plane corresponding to 6-6 of Figure 3.

Figure 7 shows in end view a different 70 form of my clamp also in its free position.

Figure 8 is a front elevation of the clamp of Figure 7.

Referring particularly to the form of clamp shown by Figures 1 to 6 inclusive; 75 this clamp comprises two cooperating jaws 9 and 10 of substantially semitubular formation, connected by a resilient member 11 of sheet formation resembling a split tube encompassing the jaws 9 and 10, and having its 80 longitudinal edges 14 and 15 of the jaws. A shield 16 is attached at the edge 15 of the above assembly, extending outwardly of the member 11, and backwardly from the edge 13 of the same. 85

The cooperating jaws 9 and 10 shown have their inner concave surfaces each of a transverse section presenting a circular arc of slightly less than 180 degrees, and similarly their convex outer surfaces. This form of 90 jaw is well adapted to general conditions; the jaws may have, however, a variety of forms to suit conditions of use, the inner surfaces for example may be straight or fluted or formed to fit the outer surface of 95 a particular body to be held thereby, and similarly the outer surfaces may be such as to give a special expansion characteristic to the clamp or to cooperate with a resilient member of different formation than is 100 shown.

The jaws 9 and 10 shown, form in effect

inward and backward extensions of the member 11, tangential thereto adjacent the edges 12 and 13. The jaws 9 and 10 are opposingly disposed, with their axes parallel and their concave surfaces presented to each other. In the free condition of the clamp as shown in Figure 5 the jaws 9 and 10 have a displaced relationship so that the longitudinal edge 17 of the jaw 9 is adjacent a mid portion of the inner concave surface of the jaw 10, and the longitudinal edge 15 of the jaw 10 is similarly located with respect to the concave inner surface of the jaw 9. This relationship results from the shape of the resilient member 11 which in its free position as shown in Figure 6 has a formation presenting in section substantially the shape of a Figure 6, and comprises substantially a three-quarter-circular cylindrical surface with tangential plane-surface forward extensions thereof. A portion of the member 11 constituting one of these extensions projects beyond their line of intersection and forms, when the clamp is assembled as shown in Figure 5, an overhanging lip extending outwardly from the mouth of the clamp as shown at 14 of Figure 5.

With the clamp assembled but in its free condition as shown in Figure 5 the resilient member 11 has substantially the same formation as before assembly, but is somewhat expanded from its own free formation, by the jaws themselves, to a larger radius of curvature of its cylindrical portion and produces an inward pressure of the jaws 9 and 10 against each other.

The jaws 9 and 10 may be attached to the member 11 in any convenient manner. In the form here shown, outward and backward extensions 18 and 19 are provided for the jaws 9 and 10 and attachment is made to these extensions by means of the tubular rivets 20 and 21, engaging the member 11 in holes 22 and 23, partly shown in Figure 6. Perforations 24 and 25 in the end portions of the member 11 give increased flexibility to these portions and provide in effect a flexible attachment of the member 11 to the jaws 9 and 10.

The shield 16 is attached also by the rivets 21, and forms a convenient handle to be used in attaching the clamp. The shield 16 is preferably made of fibre or other material having a relatively low conductivity for heat for reasons which will be hereinafter set forth. The outer edge of the shield 16 is curved to give the clamp an attractive appearance and a hole 26 is provided to receive the ball of the thumb.

The clamp may be most conveniently attached by gripping the shield between the thumb and fingers; the projecting edge 14 of Figure 5 is then hooked over the body and a suitable movement of the shield opens the mouth 14-15 of the clamp and allows pas-

sage of the body therethrough. The separation of the lips 14 and 15 is assisted by the perforated portions of the resilient member 11 so that the mid portion of the same will not be unduly flexed.

The clamp in position will assume a configuration depending on the size of the body. With the clamp in operation, as in the case of Figure 1 or Figure 4, the originally curved portion of the member 11 is expanded to a larger radius of curvature than in the free position of the clamp, whereas the originally straight portions are bent inward to a greater or less extent, depending on the size of the body gripped. These two actions combine to permit the jaws to be widely separated without straining the member 11. Also, with a comparatively large body such as 27 of Figure 4 the perforated end portions of the member 11 partially wrap themselves about the jaws 9 and 10 and are thus protected against overflexure. It will be clear also that since both the central and end portions are utilized for flexure, the wide range of extension will not necessitate a wide variation in gripping pressure.

The flexible connection provided between the jaws 9 and 10 permits these jaws to be moved rotatively with respect to each other independently of their translational movement of separation. The opposite flexure of the end and mid portions respectively of the member 11 results in an effective balance of forces over a considerable range. The jaws 9 and 10 thus may be adjusted rotatively about such a body as 27 of Figure 4, or 28 of Figure 1, to provide a greater or less separation of the edges 14 and 15, without affecting the stability of the clamp.

When used for holding hair wound on a curler spindle, one size of clamp may be used with windings of various sizes without undue variation of holding pressure, and the jaws in each case may be adjusted as previously described to provide the degree of enclosure desired. When used with a heatable spindle the clamp may also serve to insulate the wound hair from the head. The perforations 24 and 25 retard the conduction of heat to the central portion of the member 11; and the shield 16 if formed of suitable material, will insulate end portions of the member 11 adjacent thereto. Still further protection may be provided by forming the jaws 9 and 10 of fibre or other material of low conductivity for heat.

A modified form of the clamp described above is shown by Figures 7 and 8 of the drawings. In this form only one reentrant jaw 9 is provided, and this jaw is formed as one piece with the resilient member 11. A portion 29 of the resilient member 11 serves to cooperate with the jaw 9. An extension 30 of the resilient member 11 is slotted as

shown at 31 to receive the loop 32 of the shield 16. The shield in this case is formed by bending a strip to the form shown and a tip 33 is provided to join the ends of the strip. The operation of this form of clamp is substantially the same as of the form previously described.

What I claim and what I desire to secure United States Letters Patent for is:

10 1. In a clamp for a hair curler; a resilient member of semiclosed-surface formation having open ends and a mouth extending longitudinally thereof, and perforations in said member adjacent said mouth, said perforations providing increased flexibility of said member adjacent said mouth.

2. A clamp for a hair curler; said clamp comprising a resilient member and a jaw, said resilient member having a semiclosed-surface formation with open ends and longitudinal edges defining a mouth in said surface, said jaw being joined to said member adjacent one of said edges and extending inwardly of said member backwardly from 25 said edge.

3. A clamp for a hair curler; said clamp comprising a jaw of substantially semitubular formation, and a resilient member attached to said jaw adjacent a longitudinal edge thereof; said resilient member extending outwardly of said jaw and backwardly from said edge to substantially encompass said jaw.

4. An expansible clamp for a hair curler; 35 said clamp comprising jaws and a member partially encompassing said jaws forming a resilient connection between the same, said connection adapting said jaws to be moved apart by translation and also to be rotatively adjusted under operative conditions.

5. A clamp for a hair curler; said clamp comprising two jaws of substantially semitubular formation positioned with their concave surfaces adjacent, and a member substantially encompassing said jaws and forming a resilient connection between them.

6. A clamp for a hair curler; said clamp comprising jaws each having a concave surface and an edge extending longitudinally of said surface; said jaws being so positioned with respect to each other that each presents its concave surface to the concave surface of the other and each has its aforesaid edge adjacent a mid portion of the concave surface of the other.

7. A clamp for a hair curler; said clamp comprising a jaw having a substantially semicylindrical concave surface, and a second jaw having also a substantially semicylindrical concave surface; said second jaw having its concave surface presented to the concave surface of said first named jaw, and having a longitudinal edge of its con-

cave surface positioned adjacent a mid portion of the concave surface of said first named jaw.

8. In a clamp for a hair curler, said clamp comprising a resilient member of semiclosed-surface formation with open ends and two longitudinal edges defining an extensible mouth; a shield for said clamp attached to said member adjacent said mouth and extending outwardly and backwardly from said mouth, said shield being made of a material having relative to the material of said member a low conductivity for heat, said shield being thus adapted to insulate portions of said member and to serve as a handle for said clamp.

9. For a hair curler, a clamp whose internal formation comprises substantially a three-quarter-circular cylindrical surface having tangential forward extensions from the longitudinal edges thereof and tangential curved-surface inward-and-backward extensions from the first named extensions.

10. A clamp for a hair curler; said clamp having externally, substantially the form of a three-quarter-cylindrical surface having tangential plane-surface forward and backward extensions from one of its longitudinal edges, and having from its other longitudinal edge a tangential plane-surface forward extension projecting beyond the line of intersection of said extensions; the portions of 95 said clamp constituting said extensions providing lips extending outwardly from a longitudinally extending mouth adjacent the line of intersection of said extensions.

11. An expansible clamp; comprising a resilient member having substantially the form of a semiclosed cylindrical surface with a tangential plane-surface forward extension thereof, with open ends and two free adjacent longitudinal edges, and a jaw substantially semicylindrical-surface formation, attached to said member adjacent one of the longitudinal edges of the same and adjacent a longitudinal edge of said jaw, and a second jaw also of substantially semicylindrical-surface formation, attached to said member adjacent the other of said longitudinal edges thereof and adjacent a longitudinal edge of said second jaw; each of said jaws extending tangentially inwardly and backwardly from a longitudinal edge of said member, said jaws being thus opposingly disposed within said member with their longitudinal edges substantially parallel and their concave surfaces presented to each other and with a longitudinal edge of each adjacent a mid portion of the concave surface of the other.

In witness whereof I have affixed my hand this 10th day of November 1925.

WARNER T. TABB.
